UNITED STATES PATENT OFFICE.

RODOLPHUS A. ONEAL, OF OAKLAND, CALIFORNIA.

RAILWAY-TIE.

1,124,644

Specification of Letters Patent.

Patented Jan. 12, 1915.

Application filed July 22, 1913. Serial No. 780,563.

To all whom it may concern:

Be it known that I, RODOLPHUS A. ONEAL, a citizen of the United States, residing at Oakland, in the county of Alameda and State of California, have invented certain new and useful Improvements in Railway-Ties, of which the following is a specification.

This invention relates to improvements in metallic railway ties and has as its principal object the construction of such a device which will afford a resilient seat for the attached rail. It has been demonstrated by trial that the principal fault of metallic ties lies in the fact that they present an absolutely unyielding seat to the rail, whereas wood gives a cushioning effect. This same effect I aim to secure in a metallic tie by the novel construction employed.

A secend object of my invention is to provide improved means for holding the rail without the use of nuts, clamps and like devices, a single turn buckle being sufficient to secure both rails, and at the same time allow them to be more easily replaced than with the present style fastenings.

With these and other objects in view my invention consists in the novel construction and arrangement of parts as herein described and illustrated in the drawings forming a part of this specification and as more particularly pointed out in the claims hereto appended.

In the drawings:—Figure 1 is a view in perspective showing a form without a resilient seat. Fig. 2 is a view in plan of the improved tie with certain parts broken away to better disclose the construction. Fig. 3 is a view in perspective of one end of a tie showing the spring supported resilient seat. Fig. 4 is a view in section across the said seat. Fig. 5 is a view in perspective of a modified form of tie having means to prevent lateral movement of the halves. Fig. 6 is a view in horizontal section through this form.

Corresponding numerals refer to the same parts throughout the various views wherein the tie is shown constructed of the channel shaped sections 1 and 2, and in the preferred form of construction these sections have the lower flange 3 longer than the upper flange 4. The sections are held together back to back, the longer flanges adjacent forming a broad bearing surface which rests on the roadbed.

In the web of each section central there-

with I cut a rectangular opening 5 removing the metal except a short length on one end which is bent outwardly to form an ear 6. A hole is provided in this ear through which is extended the headed rod 7. A similar rod 7' passes through a hole in the ear of the second channel one rod having right hand and the other left hand threads. When the channels are placed back to back these threaded ends extend toward the center of the alining rectangular openings and there engage with a turn buckle 8. It will be seen that these rods are angularly disposed across the openings 5, so that when pulled up by the turnbuckle the tendency is to slide the sections along each other and also to draw the backs into closer contact. In the upper or short flange of each channel I form ears 9 for the purpose of holding the rail. These ears are formed by shearing through the metal of the short flange and then bending upward to conform to the base of the rail. As these ears are cut and bent in the same direction on each section it will be evident that when the channels are positioned in the tie the adjacent ears will point in opposite directions and engage the opposite edges of the rail base, and when the turnbuckle is tightened these ears will be formed against the said base clamping it securely to the tie.

In the modified form shown in Figs. 3 and 4 I secure a resilient rail seat by cutting an opening 10 in the web and extending from flange to flange directly under the said seat. As this opening is wider than the rail base a slight flexure of the top flange will take place when the rail thereon is weighted. To keep the weight of the tie down and yet secure the requisite strength at this cut out portion I prefer to reinforce the seat by placing a heavy compression spring 11 underneath the same, this spring being held in place by an elongated ring 12 formed in the lower flange.

In the form shown in Figs. 5 and 6, one end of each tie section has a rectangular notch 15 cut from the web thereof, and on the other end is formed a tongue 16 of the same size which is bent backward as clearly shown in Fig. 6, allowing a space between it and the web equal to the thickness of the web. When the two parts of this form are placed together the tongue 16 centers the corresponding notch 15 in the other member and when the parts are pulled up by the turnbuckle the web is held under the adjacent

tongue preventing any lateral and vertical movement between the parts. In use the adjacent sections 1 and 2 are moved longitudinally until the ears 9 are spaced apart sufficient to allow the rails to enter therebetween. The turnbuckle 8 is tightened moving the two sections so as to cause the ears to grip the opposite sides of the rail base and secure it in position, at the same time 10 the two sections will be drawn together due to the angular disposition of the rods. When a weight passes over the rails they will slightly depress the flange 4 over the cut out portion 10 giving a cushioning effect 15 the same as a wooden tie.

It will of course be understood that various changes in form and detail of construction may be made without departing from the spirit of my invention and that I wish 20 to cover all such modifications as fall within the scope of the appended claims.

What I claim and wish to cover by Letters Patent is:—

1. A metallic railway tie comprising two 25 channel shaped members held back to back, means for holding rails to said tie and holding said members together, a flexible rail seat formed by cutting away the web of said members under said seat, a compression 30 spring for assisting the resiliency of said seat and means on the bottom flange for positioning said spring.

2. A metallic railway tie formed of two rolled channel shaped members, said mem-

bers being placed back to back, a longitudinal central opening, flanges on opposite ends of said opening, one in each member, a connecting rod diagonally disposed through said opening, a turnbuckle in said rod, clamping means on upper flange of said 35 channel member adapted to contact with rail movement of said turnbuckle.

3. A metallic railway tie comprising the combination of two rolled channel members placed back to back, longitudinal central 40 openings formed in each of said members, lugs formed at the ends of said openings, connecting means extending diagonally through said openings engaging said lugs, and a resilient seat formed adjacent the 45 ends of said members by removing a portion of the web under said seat.

4. A metallic railway tie comprising two channel shaped members placed back to back and having a central opening in each of said members, a threaded connecting means between said members, ears formed in one flange of said members, adapted to engage a rail base, a resilient seat formed by removing the web of said channel members under 50 said seat.

In testimony whereof I affix my signature in presence of two witnesses.

RODOLPHUS A. ONEAL
